IGNITION DEVICE

Lemuel Montague Poole Davison, Ronald Russel McNaughton, and Robert Bainbridge, Trail, British Columbia, Canada, assignors to The Consolidated Mining and Smelting Company of Canada, Limited, Montreal, Quebec, Canada, a company of Canada

Application December 5, 1939, Serial No. 307,658

6 Claims. (Cl. 266—21)

This invention relates to an improved ignition device for initiating combustion in a layer of material to be sintered and is particularly applicable for use in conjunction with continuous, 5 down-draft, sintering apparatus operating on the general principles of the Dwight-Lloyd sintering machine.

In the Dwight-Lloyd process of sintering ores, wheeled pallets, each having a grate bottom, are 10 caused to travel along a continuous track. Each pallet passes progressively under a feed hopper, from which it receives its charge, thence under an ignition device, by means of which the surface of the charge is ignited, and thence over a suction "wind box" where air is drawn through the charge into the box to maintain combustion.

When sintering any material, the operation is initiated by igniting the combustible material at the surface of the charge as completely as possible, such as by applying a flame thereto for a 20 brief period of time, after which, combustion is propagated through the layer by the air currents drawn therethrough. Ignition is usually effected by means of a stationary muffle burning 25 coal, coke breeze, oil or gas and by directing the flame over the whole width of the moving charge. The burner is usually placed at one side of the machine and the flame is directed across the pallets at right angles to their movement.

30 The stationary ignition devices used heretofore, wherein the burner is placed at one side of the machine, have certain disadvantages inasmuch as the flame must be of a sufficient length to extend across the entire surface of the charge 35 in the pallets and the flame, not being of uniform temperature throughout its length, causes irregularities in ignition and distribution and a relatively high heat loss due to radiation, thus causing an unnecessarily high consumption of fuel.

40 A further difficulty is that of uniformly igniting the charge when it presents an uneven surface to the flame.

The principal object of the present invention is 45 to provide an ignition device adapted to overcome the disadvantages inherent in the stationary type burner, thereby effecting substantial savings in fuel consumption. We have attained that object by developing an oscillating, vertical-type burner designed to move at a uniform rate of 50 speed across the surface of the charge contained in the pallets and which will initiate, during its movement, the combustion of the surface layers of the material to be sintered by means of a short hot flame.

55 A further object of the invention is to construct

and assemble the ignition device in a simple manner so as to eliminate the need for separate actuating mechanism and, as far as possible, any source of mechanical failure.

An understanding of the manner in which we 5 attain the objects of our invention may be had from the following description and accompanying drawings in which the ignition device, burning a liquid fuel, is described as applied in conjunction with the well known Dwight-Lloyd 10 straight-line, continuous, sintering machine, but which may obviously be adapted to other types of sintering apparatus and to solid or gaseous fuels.

Figure 1 is a side elevation of a Dwight-Lloyd 15 straight-line sintering machine embodying our ignition device;

Figure 2 is an end elevation showing, in dotted lines, the extent of the transverse movement of the ignition device across the pallet;

Figure 3 is a top plan view of the oscillating 20 mechanism;

Figure 4 is a section along the line 4—4, Figure 3;

Figure 5 is an end elevation of Figure 4; and

Figure 6 is an enlarged view of the liquid fuel 25 burner and enclosing hood, shown partly in cross section.

Like reference characters refer to like parts throughout the specification and drawings.

The numeral 1 indicates a continuous, down-draft, straight-line sintering machine of the Dwight-Lloyd type provided with independent and unconnected pallets 2 moved in an endless train by sprockets 3 under the feeding hopper 4, under the ignition device 5 and over the suction boxes 6 respectively. Each pallet 2 is provided with wheels on which it moves except when passing over the suction boxes, at which time it slides on its planed bottom over the planed top of the suction boxes in substantially air sealing 35 engagement therewith. Dead plates 6^a are provided at each end of the suction boxes over the planed surfaces of which each pallet must move and which prevent the leakage of air into the suction boxes at those points.

45 The ignition device 5 is designed to oscillate in a pendulum-like manner over the surface of the charge in the pallets at right angles to the direction of movement of the pallets.

The ignition device 5, consists of the liquid fuel 50 burner 10, suitably connected to air and liquid fuel lines 11 and 12 respectively. The air and liquid fuel lines are flexibly connected to their sources of supply, preferably by means of rubber hose which permit their free oscillation. No 55

- special design of burner is necessary for the ignition of the fuel, but we have found that very satisfactory results are obtained from a type of burner in which a spiral vane is set to promote atomization of fuel, and mixing of fuel and combustion air, and which produces a turbulent, short, high temperature flame. The burner is enclosed in a hood 13, preferably lined with fire resistant material, as illustrated in Figure 6.
- 10] The burner 10 and enclosing hood are oscillated in a pendulum-like manner by the rotation of cam 8 which is mounted on and rotated by cam shaft 7. Cam follower 9 is mounted on shaft 9^a carried by bracket 14 which, in turn, is secured to air line 11 and liquid fuel line 12.
- 15] Cable 17 is secured to air line 11, is passed over sheave 16 and carries on its free end counterweight 15. The action of counterweight 15 holds cam follower 9 against cam 8 during its rotation, and thus prevents the ignition device from moving independently of the rotation of cam 8, at any point in its oscillation.
- 20] Cam shaft 7 is preferably rotated by the mechanism which drives the sintering machine, such as through a chain drive from the feeder mechanism as illustrated in Figures 1 and 2. The relationship between the forward movement of each pallet and the transverse oscillation of the ignition device will thus be constant, such relationship being determinable by the type of charge being sintered, and readily adjusted to suit specific conditions.
- 25] As we prefer to ignite the charge in only one direction of the movement of the ignition device, cam 8 is designed to press against cam follower 9 progressively and uniformly forwardly from the point marked "X," Figure 4, to the point marked "Y," approximately, at which latter point the ignition device will have reached its maximum distance from the vertical. Cam 8 is further designed from point Y to point X to effect the return motion of the device as rapidly as possible. The alternate uniform forward and rapid return motion of the ignition device is, of course, aided by the action of counterweight 15 which causes cam follower 9 to be retained against cam 8 during its complete rotation.
- 30] The most suitable angle at which the flame is impinged on the surface of the charge is readily determinable in practice. For example, we have found that a 40° angle between the burner axis and the surface of the charge is satisfactory.
- 35] In the operation of our ignition device, we have found it possible to reduce considerably the amount of fuel normally required by the stationary type of burner to ignite the surface of the charge contained in the pallets. In addition, it is possible to effect the uniform ignition of the surface of the charge regardless of irregularities in the surface.
- 40] It will be understood, of course, that modifications may be made to the specific embodiment of our invention, hereinbefore described and illustrated, to incorporate the principles thereof in other types of sintering apparatus without departing from the scope of the appended claims.
- 45] What we claim as new and desire to protect by Letters Patent of the United States is:
- 70] 1. In a continuous, down-draft sintering ma-

chine including a feed hopper adapted to feed a charge of material into each of a train of moving pallets, an ignition device comprising a flexibly suspended fuel burner and enclosing hood, means for oscillating said burner transversely over the surface of the charge contained in each pallet as it moves under said burner, said oscillating means being adapted to move said burner at a uniform rate of speed in one direction of its oscillation and at an accelerated rate of speed in the opposite direction.

2. In a continuous, down-draft sintering machine including a feed hopper adapted to feed a charge of material into each of a train of moving pallets, an ignition device comprising a flexibly suspended burner and enclosing hood, and rotatable cam means adapted to oscillate said burner in a pendulum-like manner transversely over the surface of the charge contained in each pallet as it moves under said burner.

3. In a continuous, down-draft sintering machine including a feed hopper adapted to feed a charge of material into each of a train of moving pallets, an ignition device comprising a flexibly suspended burner and enclosing hood, rotatable cam means adapted to oscillate said burner in a pendulum-like manner transversely over the surface of the charge contained in each pallet as it moves under said burner, and counterweight means adapted to prevent said burner from swinging freely from its flexible suspension.

4. In a continuous, down-draft sintering machine including a feed hopper adapted to feed a charge of material into each of a train of moving pallets, an ignition device comprising a flexibly suspended liquid fuel burner and enclosing hood, a rotatable cam adapted to be in continuous contact with a cam follower secured to said suspension means and counterweight means adapted to prevent said burner from swinging freely from its flexible suspension.

5. In a continuous, down-draft sintering machine including a feed hopper adapted to feed a charge of material into each of a train of moving pallets, an ignition device comprising a flexibly suspended liquid fuel burner and enclosing hood, a rotatable cam adapted to be in continuous contact with a cam follower secured to said suspension means, counterweight means adapted to prevent said burner from swinging freely from its flexible suspension and means for synchronizing the rotation of said cam with the forward movement of each of said pallets.

6. In a continuous, down-draft sintering machine including a feed hopper adapted to feed a charge of material into each of a train of moving pallets, an ignition device comprising a flexibly suspended fuel burner and enclosing hood, a rotatable cam adapted to be in continuous contact with a cam follower secured to said suspension means, said cam being designed to impart a relatively uniform forward movement and accelerated return movement to said fuel burner transversely to the direction of the movement of the charge and counterweight means adapted to prevent said burner from swinging freely from its flexible suspension.
